(57) **CLAIM**

The ornamental design for a nut and stud size gauge, as shown.

DESCRIPTION

FIG. 1 is a front view of one embodiment of a nut and stud size gauge of my new design;

FIG. 2 is a back view of the nut and stud size gauge shown in FIG. 1 of the drawings;

FIG. 3 is a bottom view of the nut and stud size gauge shown in FIG. 1 of the drawings;

FIG. 4 is a left side view of the nut and stud size gauge shown in FIG. 1 of the drawings;

FIG. 5 is a right side view of the nut and stud size gauge shown in FIG. 1 of the drawings;

FIG. 6 is a top view of the nut and stud size gauge shown in FIG. 1 of the drawings;

FIG. 7 is a perspective view of the nut and stud size gauge shown in FIG. 1 of the drawings;

FIG. 8 is a back view of another embodiment of a nut and stud size gauge of my new design;

FIG. 9 is a front view of the nut and stud size gauge shown in FIG. 8 of the drawings;

FIG. 10 is a perspective view of the nut and stud size gauge shown in FIG. 8 of the drawings;

FIG. 11 is a top view of the nut and stud size gauge shown in FIG. 8 of the drawings;

FIG. 12 is a left side view of the nut and stud size gauge shown in FIG. 8 of the drawings;

FIG. 13 is a right side view of the nut and stud size gauge shown in FIG. 8 of the drawings;

FIG. 14 is a bottom view of the nut and stud size gauge shown in FIG. 8 of the drawings;

FIG. 15 is a front view of another embodiment of nut and stud size gauge of my new design;

FIG. 16 is a perspective view of another embodiment of a nut and stud size gauge of my new design;

FIG. 17 is a front view of the nut and stud size gauge shown in FIG. 16 of the drawings;

FIG. 18 is a back view of the nut and stud size gauge shown in FIG. 16 of the drawings;

FIG. 19 is a top view of the nut and stud size gauge shown in FIG. 16 of the drawings;

FIG. 20 is a bottom view of the nut and stud size gauge shown in FIG. 16 of the drawings;

FIG. 21 is a left side view of the nut and stud size gauge shown in FIG. 16 of the drawings; and,

FIG. 22 is a right side view of the nut and stud size gauge shown in FIG. 16 of the drawings.
